Application March 21, 1931, Serial No. 524,236

4 Claims. (Cl. 123—81)

This invention relates to an internal combustion engine and is more particularly related to a sleeve valve structure for an engine of the sleeve valve type, and in its more specific aspect 5 this invention is related to a built up sleeve valve structure employing a steel sleeve to which a separate sleeve valve actuating element may be secured.

An object of this invention is to facilitate the manufacture of a sleeve valve structure for an internal combustion engine of the sleeve valve type by providing a built up sleeve valve structure consisting of a steel sleeve and a valve actuating element welded or otherwise permanently united thereto.

It is well known that a welded joint provides a rigid structure which is not readily broken and the built up sleeve structure herein illustrated provides a welded joint which may be economically and readily formed with a minimum of time and labor.

For a more detailed understanding of the invention, reference may be had to the accompanying drawing illustrating preferred embodiments 25 of the invention, and in which:

Figure 1 is a fragmentary vertical sectional view through an internal combustion engine of the sleeve valve type adapted for employing a built up sleeve valve structure constructed in accordance with this invention,

Figures 2 and 3 illustrate successive steps showing how a sleeve valve actuating element may be welded to a steel sleeve, and

Figures 4 and 5 illustrate the steps employed 35 in uniting a sleeve valve actuating element to a sleeve valve in which the joint between the sleeve valve and actuating element is constructed in a manner somewhat different from that illustrated in Figures 2 and 3.

This built up sleeve valve structure A is adapted for assembly with an internal combustion engine of the sleeve valve type which in general consists of a cylinder block 10 having a bored cylinder 11 arranged for receiving the sleeve 45 valve structure A. A piston 12 operates within the cylinder and sleeve valve structure and is preferably connected with the crankshaft 13 by means of a connecting rod 14 in the usual manner.

The sleeve valve structure A consists of a steel sleeve 15 (Figures 1 to 3 inclusive) which is provided with a wall portion 15^a adjacent to the inner end thereof of relatively greater thickness than other portions of the sleeve and this thickened wall portion may be provided with an open-

ing or window 16. A sleeve valve actuating element is adapted to be secured to the sleeve 15 and is preferably constructed of a tubular member 17 having an outwardly extending flange portion or segmental annular base 18, the flange portion 18 forming an arcuate sleeve engaging or annularly recessed portion and being adapted to overlap that portion of the sleeve valve adjacent the opening or window 16 and to be welded thereto as at 19. The base or flange portion preferably extends 10 substantially in the plane of the sleeve. This welded joint between the actuating element 17 and sleeve 15 is illustrated in Figure 3 and consists of a continuous weld about the periphery of the flange 18. Dies 20 and 21 are employed for 15 squeezing the actuating element to the sleeve in order to weld the same together under pressure. It will be noted that the sleeve valve actuating element extends transversely of the sleeve 15 and also substantially outwardly thereof. The welded 20 joint 19 substantially lies in the plane of the sleeve and the construction of this welded joint in the thickened sleeve portion provides a rigid 25 welded joint capable of carrying the loads to which such a connection is subjected.

In Figures 4 and 5 the sleeve 15' is provided with a thickened wall portion 15^b at the inner end thereof and this thickened wall portion may be provided with an opening or window 16' which is preferably larger in diameter than the tubular 30 actuating element 17'. The actuating element is provided with an outwardly extending flange portion or segmental annular base 18' at one end which is adapted to project within the opening or window 16'. The actuating element is united to the sleeve by employing dies 30, 31 and 32, said die 30 being arranged to apply pressure axially 35 of the tubular actuating element 17'. The outer edge of the flange 18' is constructed to provide a sleeve engaging portion which abuts the edge of 40 the opening or window 16' and thus when the pressure is applied to the actuating element in the welding operation the metal in the abutting portions of the actuating element and sleeve will flow together and thus provide a rigid welded 45 joint between the sleeve and actuating element which is not readily broken and which is capable of carrying the heavy loads to which said actuated element is subjected. The flange portion or segmental annular base 18' also preferably extends substantially in the plane of the sleeve 15'', but in this modified construction as shown in Figs. 4 and 5, the flange portion 18 is constructed to substantially form a continuation of the sleeve 50 wall.

55

It will be noted that the structure illustrated in the accompanying drawing provides a built up sleeve valve structure which may be readily manufactured and in view of the fact that the joint 5 between the actuating element and sleeve is preferably a welded joint located substantially in the plane of the sleeve in both instances, the joint is not easily broken nor is the sleeve or actuating element readily distorted while the same are being united or otherwise secured together.

It will be apparent to those skilled in the art to which the invention pertains, that various modifications and changes may be made therein without departing from the spirit of the invention or 10 from the scope of the appended claims.

What we claim as our invention is:

1. A built up sleeve valve structure for a sleeve valve engine and including a sleeve provided with an annular wall portion adjacent to one end 20 thereof of relatively greater thickness than other portions of said sleeve, and a sleeve valve actuating element having a base portion provided with a sleeve engaging portion complementary to the exterior surface of the relatively enlarged portion of said sleeve and secured thereto.

2. A built up sleeve valve structure for a sleeve valve engine and including a sleeve provided with an annular wall portion adjacent to one end thereof of relatively greater thickness than other 25

portions of said sleeve, and a sleeve valve actuating element provided with an enlarged flange portion overlying the exterior surface of the relatively enlarged portion of said sleeve and permanently secured thereto.

3. A built up sleeve valve structure for a sleeve valve engine and including a sleeve provided with an annular wall portion adjacent to one end thereof of relatively greater thickness than other 10 portions of said sleeve, and a sleeve valve actuating element provided with a segmental annular portion overlying the exterior surface of the relatively enlarged portion of said sleeve and permanently secured thereto.

4. A built up sleeve valve structure for a sleeve valve engine and including a sleeve provided with an annular wall portion adjacent to one end thereof of relatively greater thickness than other 15 portions of said sleeve, and a sleeve valve actuating element provided with a segmental annular portion having an annular sleeve engaging portion complementary to the exterior curved surface of the sleeve, the annular portion of said element overlying the exterior surface of the relatively enlarged portion of said sleeve and permanently secured thereto.
